UNITED STATES PATENT OFFICE.

WILLIAM E. HARRIS, OF CHICAGO, ILLINOIS.

THAWING APPARATUS.

SPECIFICATION forming part of Letters Patent No. 599,606, dated February 22, 1898.

Application filed September 18, 1897. Serial No. 652,137. (No model.)

To all whom it may concern:

Be it known that I, WILLIAM E. HARRIS, of Chicago, in the county of Cook and State of Illinois, have invented a new and Improved 5 Thawing Apparatus, of which the following is a full, clear, and exact description.

The object of the invention is to provide a new and improved apparatus for thawing frozen ground, to permit of conveniently 10 working shafts and tunnels in such ground.

The invention consists principally of a shield to be used in connection with a furnace or other heat-producing apparatus, and designed to direct and retain the heat upon 15 the face of an excavation in frozen soil and to render access to said face obtainable without removing the device.

The invention also consists of certain parts and details and combinations of the same, as 20 will be fully described hereinafter and then pointed out in the claims.

Reference is to be had to the accompanying drawings, forming a part of this specification, in which similar characters of reference indicate 25 corresponding parts in all the figures.

Figure 1 is a sectional side elevation of the improvement as applied. Fig. 2 is a plan view of the grate for the furnace. Fig. 3 is a face view of the shield, with parts in section; and Fig. 4 is a sectional plan view of 30 the same on the line 4 4 of Fig. 3.

The improved thawing apparatus is provided with a furnace A, having the conical wall of its fire-box formed by a coil of pipe 35 B, the outside of which is covered by a layer of clay C, having a shell C' inclosing the same, as is plainly indicated in Fig. 1. The upper end of the furnace A is provided with a suitable uptake C² for the escape of the 40 smoke and gases arising from the burning fuel held on a grate D, forming the bottom of the fire-box and discharging the ashes, cinders, and the like into an ash-pit E. The upper end B' of the coil of pipe B extends 45 through the uptake C² to connect outside of the furnace with a blower or like device F for forcing air through the coil of pipe and heating the air by the burning fuel on the grate D. The lower end B² of the coil of 50 pipe B is insulated in a box G, containing sand, clay, or like non-heat-conducting mate-

rial, the pipe end B² extending down through a shaft H' into the tunnel H to be formed in the frozen ground.

The end of the pipe B² in the tunnel connects with a sleeve I', held on a shield I, set against the ground at the end of the tunnel, as indicated in Fig. 1, the said shield being provided with a hollow frame I², into which opens the sleeve I', so that the heated air passing through the coil of pipe B can pass into the hollow frame. A door I³ is hinged on the said frame I², and registering apertures I⁴ and I⁵, formed in the adjacent walls of the frame and door, (see Fig. 3,) allow the heated air to 60 pass from the hollow frame I² into the hollow door I³, and perforations I⁶ in the rear face of the door allow the hot air to pass directly in contact with the frozen ground against which the shield is placed. A suitably-constructed 65 jack J serves to hold the said shield in position in the tunnel.

Now when the device is in operation and fuel is burning on the grate D in the furnace A and the blower F forces air through the 70 pipe B then this air is heated and passes in this condition into the hollow frame I² and into the hollow door I³, to finally issue through the perforations I⁶ against the frozen ground, so as to thaw the same. When this has been 75 done, the jack J is removed and the door I³ is opened to permit a miner to get at the thawed-out ground in front of the shield, so as to loosen and remove this ground through the open door. When the ground has been 80 removed, the shield I is moved forward into another part of the tunnel, and then the jack J is again applied and air is forced through the hollow frame I² and its closed door to repeat the above-described operation. The end 85 B² of the pipe B is lengthened as the work progresses, so as to make at all times a proper connection with the shield.

In order to prevent radiation of heat from the shield, I prefer to cover the front thereof 90 with wood I⁷ or other similar material.

It is understood that the heat from the frame I² thaws out sufficient ground in the immediate neighborhood of the frame to allow of removing this ground when the door 95 I³ is opened.

Having thus described my invention, I

claim as new and desire to secure by Letters Patent—

- 5 1. A thawing apparatus provided with a shield, comprising a hollow frame connected with a hot-air supply, and a hollow door hung on the said frame and in communication with the said frame, to allow the heated air to pass from the frame into the door, substantially as shown and described.
- 10 2. A thawing apparatus provided with a shield, comprising a hollow frame connected with a hot-air supply, and a hollow door hung

on the said frame and in communication with the said frame, to allow the heated air to pass from the frame into the door, said door being provided at its inner facing with apertures for the exit of the heated air to the ground against which the shield rests, substantially as shown and described. 15

WILLIAM E. HARRIS.
